CLAIM

The ornamental design for a tablet holder, as shown and described.

DESCRIPTION

FIG. 1 is a front perspective view of a tablet holder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof;

FIG. 10 is an enlarged detail view of area 10 in FIG. 1 thereof; and,

FIG. 11 is an enlarged detail view of area 11 in FIG. 1.

The broken lines in the drawings illustrate portions of the tablet holder, which form no part of the claimed design. The irregularly spaced circular shaped broken lines in FIGS. 1, 9, 10, and 11 depict the boundaries of the enlarged views and form no part of the claimed design.
